[57] CLAIM

The ornamental design for a toy boat or similar article, as shown and described.

DESCRIPTION

FIG. 1 is a perspective view of a toy boat or similar article showing our new design;

FIG. 2 is a side elevational view thereof shown on a slightly enlarged scale, the side opposite being a mirror image;

FIG. 3 is a front elevational view thereof;

FIG. 4 is a top plan view thereof;

FIG. 5 is a rear elevational view thereof; and,

FIG. 6 is a bottom plan view thereof.
